[57] CLAIM

The ornamental design for a telephone cradle, substantially as shown and described.

DESCRIPTION

FIG. 1 is a left side, top and partial front side perspective view of a telephone cradle showing our new design;

FIG. 2 is a left side elevational view thereof, the side opposite being a mirror image;

FIG. 3 is a bottom plan view thereof;

FIG. 4 is a top plan view thereof;

FIG. 5 is a rear elevational view of the telephone cradle; and

FIG. 6 is a front elevational view thereof.
